8 Claims. (Cl. 250—27)

1

The invention herein described and claimed relates to an improved frequency-dividing circuit of the counting type. The improved circuit is adapted to achieve frequency division, of high count-down ratio, with excellent stability. For example, the circuit is capable of accomplishing frequency division of excellent stability with a divisor as large as twenty or more. This is in contrast to conventional counting circuits which are ordinarily unable to divide by a factor larger than six or eight without losing stability.

The operation of the improved circuit of the present invention is similar in some respects to that of prior art circuits in that frequency division is effected by cumulating a voltage in incremental fashion and utilizing a cumulative voltage of predetermined magnitude to trigger a blocking tube oscillator, thus to produce pulses at a sub-frequency of the frequency of the applied pulses.

The improved circuit of the present invention is quite different, however, from that of prior art circuits in that the new circuit includes means which enable the circuit to produce, from recurrent applied pulses of substantially equal amplitude, voltage increments of increasing amplitude. This is in contrast to most prior art circuits which derive, from recurrent applied pulses of equal amplitude, voltage increments of decreasing amplitude.

Stated graphically, the present invention provides a counting circuit capable of producing a voltage staircase whose risers increase in amplitude. Thus, in the preferred manner of operation, the riser which effects firing of the blocking oscillator tube, is larger in amplitude than the first step of the staircase. Positive and dependable firing action is thus assured. Most prior art circuits, on the other hand, produce a voltage staircase whose risers decrease in amplitude; hence, the amplitude of the riser intended to effect firing may be too small to assure dependable counting action.

If desired, the new circuit may be so operated that the lower steps of the voltage staircase diminish in amplitude in customary manner, reserving the increase in riser amplitudes to the higher steps, particularly the steps immediately prior to, and including, the trigger step which is intended to fire the blocking oscillator. Or, if desired, the new circuit may be so adjusted as to produce a voltage staircase whose risers are substantially equal in amplitude.

While I know of several other frequency-dividing circuits of the counting type capable of pro-

2

ducing voltage staircases whose risers are of substantially constant amplitude, I know of no other frequency-dividing circuit capable of producing a voltage staircase whose risers increase in amplitude. It will be apparent to those skilled in the art that my new circuit is capable of achieving very accurate and stable frequency division since the riser intended to effect firing may be made of adequate amplitude to assure dependable action.

It is an object of this invention to provide a frequency-dividing circuit of the counting type capable of effecting accurate division with divisors as large as twenty or more.

It is another object of this invention to provide a frequency-dividing circuit adapted to develop, from successively applied voltage pulses of substantially equal amplitude, voltage increments of increasing magnitude, whereby the trigger step of the voltage staircase may be larger than the first step.

Another object of this invention is to provide, in a frequency-dividing circuit of the counting type, means for compensating, and, in the preferred manner of operation, over-compensating, for the exponential decrease in the amplitude of the incremental voltages which ordinarily characterizes conventional counting circuits.

These and other objects, advantages and features of the present invention, and the manner in which the objects are attained, will become clear from a consideration of the following detailed description and of the accompanying drawing wherein:

Figure 1 is a schematic representation of a preferred form of my improved frequency-dividing circuit; and

Figures 2 and 3 are graphical representations which will be helpful in describing and understanding the present invention.

Referring now to Figure 1, there is shown a frequency-dividing circuit of the counting type comprising a source 10 of voltage pulses, a slightly modified but otherwise conventional step-by-step counting circuit 11, a blocking tube oscillator circuit 12, and, in accordance with the present invention, a compensating or booster circuit 14.

Source 10 may conveniently comprise a cathode-follower driver circuit represented generally at 13 which delivers positive voltage pulses of substantially equal amplitude through an internal resistance 15.

Circuit 11 comprises a coupling capacitor 16, a charge diode 17, a discharge diode 18, and a storage capacitor 19. Storage capacitor 19 will be quite large, ordinarily, relative to coupling

capacitor 16. For example, storage capacitor 19 may be fifty times larger than coupling capacitor 16. The cathode of charge diode 17 is connected in the manner shown in the drawing, to the upper plate of storage capacitor 19, to the grid 20 of booster tube 21, and, by way of winding 22 of transformer 23, to the grid 24 of blocking oscillator tube 25. The anode of charge diode 17 is connected to the cathode of discharge diode 18 and to the low potential plate of coupling capacitor 16. The anode of discharge diode 18 is connected to a source of negative direct-current potential, B--.

Circuit 12 may conveniently comprise a known form of blocking tube oscillator including a triode 25 and a pulse transformer 23 whose primary winding 26 is connected between the anode 27 of the triode 25 and a source of positive plate potential, B+. The secondary winding 22 of pulse transformer 23 is connected, as previously indicated, between the grid 24 of tube 25 and the upper plate of storage capacitor 19. The cathode 28 of tube 25 may be connected directly to ground. The sub-multiple frequency output of the counting circuit may be taken between the plate 27 of oscillator tube 25 and ground, as shown in Figure 1.

Compensating or booster circuit 14 comprises a tube 21 whose cathode 29 is connected, by way of a load resistor 30, to a source of negative direct-current potential, B--. The potential of the supply voltage, B-, is higher than that of the supply voltage, B--, connected to the anode of diode 18. The voltage difference between B- and B-- constitutes the fixed bias on booster tube 21, as will become clear. Storage capacitor 19 is connected directly between cathode 29 and grid 20 of tube 21. Plate 31 of tube 21 is connected to a source of positive plate voltage, B+.

It will be seen that, except for the compensating or booster circuit 14, the circuit of the present invention is similar to the conventional prior art counting circuit. In the prior art circuit, the low potential plate of storage capacitor 19 is connected directly to ground.

Referring now to Figures 2 and 3, there is shown, in Figure 2, a graphical representation of the charge developed in step-by-step fashion across storage capacitor 19, and, in Figure 3, there is shown a graphical representation of the staircase voltage developed in step-by-step fashion between the grid 24 and cathode 28 of oscillator tube 25.

The operation of the circuit will now be described. Assume that blocking oscillator tube 25 has fired and that storage capacitor 19 has just been discharged through resistor 30 by the grid current of oscillator tube 25. Assume that tube 25 has now been cut off, and that the circuit is awaiting the arrival of the next pulse. At this stage in the operation of the circuit, the potential of grid 24 of oscillator tube 25, and of the upper plate of capacitor 19 (point d in the circuit of Figure 1), is at a value which corresponds to the voltage at the bottom of the staircases depicted graphically in Figures 2 and 3. It will be seen that the value of the voltage at the bottom of the staircase is determined by the value of negative supply voltage, B--, connected to the anode of diode 18. For, when tube 25 fires and grid current flows to discharge capacitor 19, the upper plate of capacitor 19 is driven down to a potential limited by, and hence substantially equal to, the voltage of the nega-

tive supply, B--. For example, the supply voltage, B--, may be minus fifty-five volts, as is indicated in Figure 1. In such case, the voltage at the bottom of the staircase of Figures 2 and 3 is substantially minus fifty-five volts. This voltage, i.e., the voltage of the negative supply, B--, appearing on grid 24 and on the upper plate of capacitor 19 when tube 25 cuts off, also appears on grid 20 of booster tube 21.

10 The potential of cathode 29 of tube 21 (point e in Figure 1), prior to the arrival of the first pulse following discharge, is higher than that of point d, the potential of point e being equal to that of the negative supply voltage, B--, which, 15 by way of example, may be minus fifteen volts. Hence, the fixed bias on tube 21 is the voltage difference between the negative supply voltages, B-- and B-, which, in the present example, is minus forty volts. This voltage appears, then, 20 across capacitor 19 prior to the arrival of the first pulse following discharge.

When the leading edge of the first pulse following discharge arrives, the potentials on both 25 sides of coupling capacitor 16 rise by an amount equal to the amplitude of the pulse. Diode 17 thereupon conducts, but diode 18 remains non-conductive. During conduction, diode 17 comprises a virtual short circuit; its relative resistance is extremely low, and the voltage drop thereacross is negligible. The potentials of both 30 sides of capacitor 19 rise by an amount equal substantially to the amplitude of the applied pulse, and the pulse voltage is impressed across resistor 30. Resistor 30 is of relatively small value, 35 and capacitors 16 and 19 quickly charge, in inverse proportion to their respective capacitances. The R. C. time constant of the charging circuit is substantially shorter than the duration of the applied pulse. For example, in a typical case, 40 the R. C. time constant may be of the order of one microsecond, and the pulse duration may be five microseconds. Capacitors 16 and 19 therefore charge to their full extent prior to the termination of the pulse. The values of 45 capacitors 16 and 19 are so selected, with respect to each other, that a desired division of the applied pulse voltage is effected therebetween, and a desired proportion of the voltage of each pulse is developed across storage capacitor 19.

50 When the trailing edge of the first pulse arrives, both sides of capacitor 16 suddenly drop in potential by an amount substantially equal to the magnitude of the pulse. The cathode of diode 18 is then at a lower potential than the anode. Diode 55 18 thereupon conducts, while diode 17 ceases to conduct. Capacitor 16 discharges through diode 18 until the potential of point c rises to the potential of the supply voltage, B--, which, in the present example, has been assumed to be minus fifty-five volts. The potential of the cathode of diode 17 is now higher than that of the anode, i. e., the potential of point d is now higher than that of point c by the amount of charge developed across capacitor 19 by the first pulse. This charge 60 is held on capacitor 19 for there is no discharge path to the lower plate of capacitor 19 (diode 17, tube 21, and tube 25 all being in non-conductive condition). The charge developed across capacitor 19 by the first pulse is represented in Figures 65 2 and 3 by the first riser. The potential of the cathode of tube 21, point e in the circuit of Figure 1, remains equal to that of the supply voltage, B-, so long as tube 21 remains in a non-conductive state. In the present example, point e is minus 70 fifteen volts, when tube 21 is non-conductive.

I have just described that, as a result of the first pulse, the potential of point *d* was increased while the potential of point *e* remained unchanged. Stated another way, the first pulse effected a decrease in the negative grid-to-cathode voltage on tube 21, the magnitude of the decrease being equal to the incremental charge developed across capacitor 19. Assume that this decrease in negative polarity of grid 20 was insufficient to cause tube 21 to conduct, and that tube 21 remains non-conductive following the first pulse.

When the leading edge of the second pulse arrives, diode 17 does not conduct until point *c* has risen to the potential of point *d*. Thereupon diode 17 conducts. Diode 18, of course, remains non-conductive throughout the duration of the pulse. It will be seen that only the voltage difference, between the amplitude of the applied pulse and the charge across capacitor 19 derived from the previously applied pulse, is divided proportionately between capacitors 16 and 19. Hence, the second pulse is effective to develop across capacitor 19 a voltage increment whose magnitude is less than that developed thereacross by the first pulse. The second riser of the voltage staircases of Figure 2 and 3 is therefore shown to be smaller in amplitude than that of the first riser.

The grid-to-cathode voltage on tube 21 has now been made less negative by the sum of the charges developed across capacitor 19 by the first two pulses. Assume that this decrease in the negative polarity of grid 20 is not sufficient to permit tube 21 to conduct. The potential of cathode 29 (point *e*) therefore remains unchanged.

The action described above continues, as is indicated in Figures 2 and 3 by the third, fourth and fifth staircase risers of decreasing amplitude, until the potential of grid 20, with respect to that of cathode 29, is raised sufficiently to cause tube 21 to conduct. When this occurs, plate current flows through load resistor 30, and the potential of cathode 29 and of the lower plate of capacitor 19 (point *e* in the circuit of Figure 1) becomes positive with respect to that of the supply voltage, *B*-. In other words, the potential of the lower plate of capacitor 19, heretofore at the potential of the supply voltage, *B*-, rises by the amount of the voltage drop across load resistor 30. And, since no charging path exists, the upper plate of capacitor 19 rises by an equal amount.

Observe then that the conduction of booster tube 21 causes no change in the grid-to-cathode voltage of the tube since no charge is developed across capacitor 19 as a result of the tube conducting. Note, however, that while the grid-to-cathode voltage of booster tube 21 remains unchanged, the grid-to-cathode voltage of the blocking oscillator tube 25 does change when the booster tube 21 conducts, for the potential of point *d* has risen, with respect to ground, by the amount of voltage developed across load resistor 30.

Assume that, in the present example, booster tube 21 conducts for the first time when the sixth pulse is received. The incremental charge developed across capacitor 19 by the sixth pulse is smaller than that developed by any of the five preceding pulses, for the reasons previously described. This is shown graphically in Figure 2. But, due to tube 21 conducting when the sixth pulse arrives, the potential at point *d* with respect to ground rises as a result of the voltage drop across resistor 30. This rise is in addition to the incremental charge developed across capacitor

19 by the sixth pulse. The total rise in the grid-to-cathode voltage of oscillator tube 25, as a result of the arrival of the sixth pulse, is therefore the sum of two components. And, if the circuit constants be properly selected, this sum may be larger than the increase occasioned by the fifth pulse. The sixth riser in Figure 3 is, therefore, shown to be larger than the fifth.

Following the termination of the pulse which caused booster tube 21 to conduct (the sixth pulse in the present illustration), tube 21 continues to conduct. As the succeeding pulses arrive, capacitor 19 is charged incrementally by each pulse, the magnitude of each increment being less than that of previous increments. This is shown graphically in Figure 2. The grid-to-cathode voltage of booster tube 21 thus becomes less and less negative, or more and more positive, in step-by-step fashion in a manner corresponding to the staircase of Figure 2, and the plate current through load resistor 30 becomes larger and larger. As a result, the voltage drop across load resistor 30 increases step by step and the potential of point *e*, and hence of point *d*, becomes more and more positive in step-by-step manner relative to the voltage source, *B*-.

Observe that the total change occurring in the grid-to-cathode voltage of blocking oscillator tube 25 as each pulse is received is equal to the change in voltage occurring between point *d* and ground. As described above, this change is comprised of two components, one of which is the incremental charge developed by each pulse across capacitor 19. The other component is the rise occasioned by each pulse in the potentials of points *e* and *d*, which as described above results from the rise in the grid-to-cathode voltage of tube 21 and the increase in plate current through load resistor 30. The magnitude of the latter component is a function of the selected circuit constants, including the gain of tube 21. This component may be of such magnitude that, when added to the incremental charge developed across capacitor 19 by an applied pulse, the sum may constitute a voltage change as large as, or larger than, that of the first riser of the staircase. This is shown graphically in Figure 3 which, as previously indicated, depicts the step-by-step change in the grid-to-cathode voltage of the blocking oscillator tube 25. In Figure 3, the point at which booster tube 21 begins to conduct is appropriately marked, as is the potential at which the blocking oscillator tube 25 fires.

It will be understood that tube 21 operates as an amplifier tube and not as a cathode follower, for the voltage developed in step-by-step fashion across capacitor 19 is applied directly between the grid 20 and cathode 29 of tube 21. Observe that the voltage is not applied between the grid 20 and the low potential end of the cathode load resistor 30, as would be the case in cathode-follower operation. By suitable selection of circuit constants, the gain of tube 21 may be made substantially as large as desired. The amount of gain desired will depend, among other things, upon the count-down ratio desired to be achieved. In general, the larger the frequency division to be effected, the smaller the gain desired.

It will be apparent to those skilled in the art that in some instances, as, for example, where the divisor is relatively small, the circuit parameters, particularly the fixed bias, may be so selected that tube 21 begins to conduct upon arrival of the first pulse of the cycle, i. e., upon arrival of the first pulse following the firing of

oscillator tube 25 and the discharge of capacitor 19. In such case, all of the risers of the voltage staircase of Figure 3 may be of increasing amplitude.

If desired, all of the risers of the voltage staircase may be made of substantially equal amplitude. This may be accomplished by so selecting the circuit parameters that the decreasing rate of rise in the voltage developed across capacitor 19 is substantially compensated by an increasing rate of rise in the voltage developed across load resistor 30. The change occurring in the potential of point d with respect to ground will then be linear. Ordinarily, however, it will be more desirable to develop a staircase whose slope or rate of rise increases.

It will be understood that such things as the slope of the staircase and the number of staircase steps required to effect firing of the blocking oscillator tube are functions of the circuit constants, including such parameters as the fixed bias on tube 21, the plate-current grid-voltage characteristic or mutual conductance of tube 21, the value of load resistor 30, and the relative values of capacitors 16 and 19. For example, increasing the fixed bias of tube 21, other things remaining unchanged, will increase the number of steps required to effect firing of blocking oscillator tube 25, whereas increasing the value of load resistor 30 will increase the rate of rise or slope of the staircase, and, other things remaining unchanged, will decrease the number of steps required to effect firing.

Indicated in Figure 1 are the circuit constants used in a particular frequency-divider circuit which I have built in accordance with the present invention and which has produced very satisfactory results. The constants shown are, of course, by way of illustration only and are not intended to be limiting.

Having described my invention, I claim:

1. A frequency-dividing circuit comprising: a blocking tube oscillator; a source of recurrent voltage pulses of substantially equal amplitude; means, including a storage capacitor, responsive to said recurrent voltage pulses for cumulating incremental voltages whose amplitudes successively decrease; means, including an amplifier tube, responsive to said cumulating incremental voltages for developing and cumulating other incremental voltages whose amplitudes successively increase; means for combining additively in an aiding sense both of said cumulating voltages; and means for applying said combined voltages to said blocking tube oscillator.

2. A frequency-dividing circuit comprising: a blocking tube oscillator; an amplifier tube having at least cathode, plate and grid electrodes and having a load impedance in its plate-to-cathode circuit; a voltage-divider circuit comprising a first capacitor and a second capacitor; a source of recurrent voltage pulses of substantially equal amplitude; means for connecting said source across said voltage-divider circuit; means for effecting discharge of said first capacitor in the intervals between pulses while maintaining the charge on second capacitor, whereby a voltage cumulates in step-by-step manner across said second capacitor; means for applying said cumulating voltage between the grid and cathode of said amplifier tube to develop an output voltage across said load impedance, the amplitude of said output voltage being a function of said applied voltage; means for combining additively in an aiding sense the cumulating voltage de-

veloped across said second capacitor and the output voltage developed across said load impedance of said amplifier; and means for applying said combined voltage to said blocking tube oscillator.

3. A frequency-dividing circuit comprising: a blocking tube oscillator; an amplifier tube having at least cathode, plate and grid electrodes and having a load impedance in its plate-to-cathode circuit; a voltage-divider circuit comprising a first capacitor and a second capacitor; a first diode; a second diode; a source of recurrent voltage pulses of substantially equal amplitude; means for connecting said source across said voltage-divider circuit; means for so connecting said first diode to said first capacitor as to effect discharge of said capacitor in the intervals between pulses; means for connecting said second diode to said second capacitor as to oppose discharge of said second capacitor during the intervals between pulses, whereby a first staircase voltage develops in step-by-step fashion across said second capacitor; means for applying said staircase voltage between the grid and cathode of said amplifier tube to develop across said load impedance a second staircase voltage whose slope is of the same polarity as that of said first staircase voltage; means for combining additively said first and second staircase voltages; and means for applying said combined voltages to said blocking tube oscillator.

4. A frequency-dividing circuit comprising: a blocking tube oscillator; an amplifier tube having at least cathode, plate and grid electrodes and having a load resistance in its plate-to-cathode circuit; a voltage-divider circuit comprising a first capacitor and a second capacitor; a first diode; a second diode; a source of recurrent voltage pulses of substantially equal amplitude; means for connecting said source across said voltage-divider circuit; means for so connecting said first diode to said first capacitor as to effect discharge of said capacitor in the intervals between pulses; means for so connecting said second diode to said second capacitor as to oppose discharge of said second capacitor during the intervals between pulses, whereby a first staircase voltage develops in step-by-step fashion across said second capacitor, said first staircase voltage having a decreasing rate of rise; means for applying said first staircase voltage between the grid and cathode of said amplifier tube to develop across said load impedance a second staircase voltage whose slope is of the same polarity as that of said first staircase voltage; means for combining additively said first and second staircase voltages and means for applying said combined voltages to said blocking tube oscillator.

5. A frequency-dividing circuit comprising: a blocking tube oscillator; a source of recurrent voltage pulses of substantially equal amplitude; a voltage-divider circuit comprising a coupling capacitor and a storage capacitor; means for applying said voltage pulses across said voltage-divider circuit; means, including a first rectifier element connected between said coupling capacitor and said storage capacitor, for maintaining the voltage developed across said storage capacitor; means, including a second rectifier element connected between said coupling capacitor and a point of reference potential, for discharging said coupling capacitor to said reference potential in the intervals between pulses; an amplifier tube having at least cathode, plate and grid electrodes and having a cathode load im-

pedance in the plate-to-cathode circuit; means for applying the voltage developed across said storage capacitor between the grid and cathode of said amplifier tube to develop a voltage of the same polarity across the said cathode load impedance; means for combining additively the voltage developed across said cathode load impedance and the voltage developed across said storage capacitor; and means for applying said combined voltages to said blocking tube oscillator.

6. A frequency-dividing circuit comprising: a blocking tube oscillator; a source of recurrent voltage pulses of substantially equal amplitude; a voltage-divider circuit including a coupling capacitor, a storage capacitor and a first rectifying element connected in series between said capacitors; means for cumulating across said storage capacitor in step-by-step fashion incremental voltages of decreasing amplitude, said cumulating means including a second rectifying element, one electrode of said second rectifying element being connected to the common junction of one side of said coupling capacitor and a different electrode of said first rectifying element, the other electrode of said second rectifying element being connected to a point of low reference potential; an amplifier tube having at least cathode, a plate and grid electrodes and having a cathode load impedance in the plate-to-cathode circuit; means for applying the voltage developed across said storage capacitor between the grid and cathode of said amplifier tube; means for combining additively the voltage developed across said cathode load impedance of said amplifier tube and the voltage accumulated across said storage capacitor; and means for applying said combined voltages to said blocking tube oscillator.

7. A frequency-dividing circuit comprising: a blocking tube oscillator; a source of recurrent voltage pulses of substantially equal amplitude; means, including a storage capacitor, responsive to said recurrent voltage pulses for developing a first voltage of stair-step waveform; means, including an amplifier tube, responsive to said first stair-step voltage for developing a second voltage of stair-step waveform whose slope is of the same polarity as that of said first stair-step voltage; means for combining additively said first and second stair-step voltages; and means for applying said combined voltages to said blocking tube oscillator.
- 15 8. A frequency-dividing circuit comprising: a blocking tube oscillator; a source of recurrent voltage pulses of substantially equal amplitude; means, including a storage capacitor, responsive to said recurrent voltage pulses for developing a first voltage of stair-step waveform; means responsive to said first stair-step voltage for developing a second voltage of stair-step waveform whose slope is of the same polarity as that of said first stair-step voltage; means for combining additively said first and second stair-step voltages; and means for applying said combined voltages to said blocking tube oscillator.
